ABSTRACT OF THE DISCLOSURE

A high wattage, compact arc high pressure discharge lamp having a rare gas and/or metal vapor filling using internal gas circulation by cathodic plasma jet action to produce cooling.

High pressure compact arc type (i.e. arc electrodes placed relatively close together rather than at the ends of an elongated tube) discharge lamps with either rare gas or metal vapor filling, have recently found increased usage in optical equipment. Typical applications include the use of these lamps as light or radiation sources for searchlights, projectors, and devices that simulate the sun's radiation in outer space for the purpose of testing space vehicles or their components. Lamps of this type are very suitable for such equipment because they provide a stable source of radiation with a very high brightness and good luminous efficacy. They also operate cleanly without adjustment or maintenance for hundreds or even thousands, of hours.

Because of their many advantages, high pressure compact arc-type lamps are increasingly replacing carbon arc type lamps which were previously used in many of the aforementioned applications. Since carbon arc lamps are available or can be built for input wattage ratings up to 20, 50 or even 100 kilowatts, it is desirable to provide compact arc discharge lamps having similar high wattage ratings. This demand has been partly met through development of rare gas (xenon) high pressure compact arc lamps having input ratings in the 10-30 kilowatt range. Lamps of this general type are described in an article entitled "High Brightness Xenon Lamps with Liquid-Cooled Electrodes" by W. E. Thouret, H. S. Strauss, S. F. Cortorillo, H. Kee, in Illuminating Engineering, vol. 60 page 399, 1965.

For lamps with a rare gas filling, such as xenon, an input wattage rating exists above which economic and reliable lamp designs cannot be obtained without using forced cooling of the electrodes. This limit presently seems to lie somewhere between 10 and 20 kilowatts, depending upon the particular conditions of the application for which the lamp is to be used. The use of forced cooling of the electrodes increases the wattage rating of compact arc type lamps to a considerable degree. For example, high brightness xenon lamps in the 20 to 30 kilowatt input range have been developed using liquid cooled electrodes and seals. Such lamps operate economically and reliably, because due to the liquid cooling, quartz-to-metal seals of relatively simple construction can be used. The electrodes of these fluid-cooled lamps

2

are capable of carrying currents up to 1000 amperes and they have practically unlimited life because they operate at only slightly elevated temperatures. One such liquid cooled lamp is described in the copending application of W. E. Thouret, S.N. 586,065 filed Oct. 12, 1966 entitled "Compact Arc High Pressure Discharge Lamp with Liquid Cooled Electrodes and Halogen Cycle," and assigned to the same assignee.

The lives of lamps with uncooled seals and electrodes are usually terminated by seal failure, because the seals have to be operated at a temperature of several hundred degrees centigrade. In general it can be said that liquid cooled electrodes are highly advantageous for large wattage compact arc lamps because they allow both the use of smaller bulbs for the same wattage as an uncooled lamp and the use of simplified high current seals. However, even when liquid cooled electrodes are used, the bulb dimensions required for reliable, long lamp life designs become quite large when the total lamp input exceeds 20 kilowatts. It has been found, for example, that in a compact arc lamp with liquid cooled electrodes the quartz bulb cannot be loaded to more than approximately 45 watts/cm.² or 280 watts/sq. in. of the lamp input wattage. If loaded higher, the operating temperature of the quartz bulb increases into the range in which "structural changes" occur fast enough in fused quartz to reduce the mechanical strength of the envelope during the expected useful life of the lamp. The term "structural changes" is used to mean all changes that lead to a decrease in tensile strength, for example, local recrystallization.

In general it has been found that the bulb operating temperature of a compact arc discharge lamp and, consequently, the applicable specific bulb surface loading in watts/cm.² is determined by that part of the lamp input power (wattage which is the product of lamp current and applied voltage) that is not converted into radiation for which the lamp bulb is transparent. More or less rough estimates and calculations lead to the following distribution of the input energy for high wattage compact arc lamps with quartz bulb and liquid cooled electrodes:

	Percent
(a) Radiation from the arc plasma and electrodes that passes unabsorbed through the bulb	40
(b) Radiation from the arc plasma and electrodes that is absorbed by the bulb (longwave infrared and shortwave ultraviolet radiation)	5
(c) Energy removed through the cooling liquid from the electrodes	35
(d) Energy transferred from the arc to the bulb by heat conduction	5
(e) Energy transferred from the arc to the bulb by gas convection	15
Total input wattage	100

Due to the inherent properties of compact arc lamp design, the ultimate disposition of the input energy in items (a) to (d) cannot be changed to any significant degree through modification of the lamp internal construction. Therefore, item (e) appears to present the most promising area in which improvement resulting in higher surface loading can be achieved.

The energy balance table given above indicates that only items (b), (d), and (e) contribute energy that remains within the bulb and causes its temperature to rise. These three items amount in total to about 25% of the lamp input. As seen, 60% of the bulb heating energy of items (b), (d) and (e) is supplied by item (e), the energy transferred from the arc to the bulb by gas convection (15%). If a part of this convection energy can be removed from the lamp before it reaches the bulb, the specific surface loading of the bulb in watts/cm.² can be increased. For example, if 80% of the gas convection energy can be removed the surface loading of a given bulb can be raised substantially, and perhaps be nearly doubled. This means that, for example, the bulb size that now is sufficient for reliable operation of a 30 kw. input lamp would be satisfactory for a lamp with 50 to 60 kw. input.

For the purpose of removing the energy carried through gas convection from the extremely hot plasma (in the order of 6000 to 10000° K.) to the lamp bulb, it previously has been suggested to circulate the gas through an external vacuum-tight and pressurized heat exchange system. While such gas circulating systems operate to a measure to produce the desired result they have several disadvantages. For example, they are quite intricate and they considerably add to the complications and service problems connected with the operation of high powered arc lamps with liquid cooled electrodes.

The present invention provides a compact arc high-pressure lamp in which provisions are made to remove considerably more heat from the inner lamp volume than is possible through the use of water-cooled electrodes of conventional design. Thus the quartz bulb can be loaded higher and either smaller, less costly bulbs can be used for the same wattage or much higher wattages can be applied without increasing the bulb size.

In accordance with the invention, the hot plasma gas is circulated through a channel, or channels provided in one or both of the electrodes, by means of the cathodic plasma jet inherent to direct current high wattage compact arcs.

The plasma gas circulation is achieved within the lamp, without the use of an external pump and/or heat exchange system, through utilization of the cathodic plasma jet. As is well known to those skilled in the art the cathodic plasma jet provides powerful acceleration of the plasma gas in a direction from the cathode toward the anode parallel to the arc axis independent of the lamp's burning position. The gas in the plasma jet reaches typical velocities of 500 to 1000 feet/second. By using the plasma jet action, in accordance with the present invention, a large portion of the energy (as much as 80%) usually transferred from the arc to the bulb by gas convection is taken up by a cooling liquid which is preferably circulated through the anode. This as explained previously, permits an increase in the surface loading of the bulb.

It is therefore an object of the present invention to provide a compact arc type discharge lamp in which a portion of the plasma is cooled.

A further object is to provide a compact arc type discharge lamp having an anode construction which permits the circulation of heated gas to come into contact with a cooling medium through cathodic jet action and constricts the size of the arc.

Another object is to provide a compact arc type discharge lamp in which cathodic jet action of the plasma is utilized to cool the gas within the lamp.

An additional object is to provide a compact arc type discharge lamp having novel constructions for the anode and cathode electrodes which constrict the arc size and enhance cooling of the gas within the tube.

Other objects and advantages of the present invention will become more apparent upon consideration of the following specification and annexed drawings in which:

FIG. 1 is a cross-sectional view of one embodiment of lamp made in accordance with the present invention.

FIG. 1A is a cross-sectional view of the anode portion of the lamp of FIG. 1, turned 90°.

FIG. 2 is a cross-sectional view of the cathode portion of another embodiment of lamp made in accordance with the present invention.

FIGS. 1 and 1A show in cross-section a high pressure rare gas or metal vapor filled high, wattage compact arc lamp designed according to this invention. The lamp has a spherical or nearly spherical bulb 1 with two integral, generally cylindrical extensions 12 and 13. The bulb 1 and its extensions are preferably made of a suitable refractory, transparent or translucent material such as quartz.

Mounted within the respective extensions 12 and 13 are the anode and cathode electrodes 16 and 17 which are generally cylindrical in shape and are hollow for a substantial portion of their lengths. The electrodes 16 and 17 are preferably made as thick walled tubes of molybdenum, nickel, stainless steel or a similar suitable metal. Current is supplied to each electrodes 16 and 17 by a suitable cable (not shown) and a fluid supply and return (not shown) are also connected to the outer ends of the electrodes.

The anode electrode 16 has a tip 18 thereon with a rounded outer edge 19. The cathode electrode 17 has a tip 20 with a pointed end 21. Both tips 18 and 20 are made of massive tungsten or another suitable refractory metal. The anode tip 18 is brazed vacuum-tight to the anode tube 16 at 22 while the cathode tip 20 is riveted to the cathode tube 17 at 24. The cathode tip has a shouldered down portion 25 which accommodates the rivet 24. The two tips 18 and 20 of the electrodes are disposed opposite each other so that an arc is struck therebetween when current is applied to the electrodes.

The electrodes 16 and 17 are sealed, vacuum-tight, to the bulb by reentrant, or folded back, portions 28 of the extensions 12 and 13 and cups 29, which are of a suitable material such as Kovar. The reduced diameter portions of each of the cups 29 is sealed to the electrode while the larger diameter portion is sealed to the end of an area 30 of graded glass seals which extends from reentrant portions 28 to the end of the cup. The graded seals comprise a plurality of different glasses with graded expansion coefficients. The purpose of these seals is to bridge the difference between the expansion coefficients of the cup material and the bulb material.

A lateral support 31 is anchored within the bulb wall near the end of each electrode tube 16 and 17. These supports firmly hold and locate the inner ends of the electrodes and prevent any bending stresses within the glass seals. The supports are made of a suitable material, such as tungsten. A gettering material such as a piece of tantalum or titanium sheet 34 is fastened around the shank of the cathode tip as a getter substance to collect certain impurities which are produced during lamp manufacture and operation.

As shown in FIGS. 1 and 1A, the anode tip 18 is hollow or ring-shaped and has an axially located hole 35. The hole 35 communicates with a passage formed by a tube 36 of metal in the end of anode electrode tube 16. Tube 36 branches out into two metal tubes 37 and 38 which are generally at right angles, to form a generally T-shaped passageway communicating with the hole 35 in the anode tip.

As shown more clearly in FIG. 1A, the interior of the anode tube 16 is supplied with cooling fluid from a conduit 40 which branches out near tubes 37 and 38 into two conduits 41. The end of anode electrode tube 16 is sealed by the tip 18 and tube 36. The cooling fluid returns to its source through the portion of the anode tube surrounding the cooling conduits. The walls of tubes 36, 37, 38 are preferably thin to afford the maximum amount of heat transfer and their walls are completely surrounded

by the cooling fluid from conduit 40. The cooling fluid source and return connections are not shown since they are conventional in the art.

When the lamp is operated an arc is struck between the opposing tips of the electrodes and a hot plasma stream is produced. This is shown by the lines 40 in FIG. 1. The hole 35 in the anode tip 18 leads the hot plasma stream into the thin walled T-shaped metal tube 36, 37, 38 which is completely surrounded by the cooling fluid that cools the anode tip 18 (see FIG. 1A). The connections between anode tip 18, T-shaped tubes 36, 37, 38 and main anode tube 16 are all made vacuum-tight through vacuum-brazing, electron beam, welding or other suitable processes. The T-tube 36, 37, 38 is so dimensioned that the fast moving plasma gas stream becomes turbulent and loses a large portion of its heat to the surrounding fluid cooled metal walls thereby reducing the temperature of the stream as it leaves the passages formed by tubes 37 and 38. As indicated in FIG. 1 by the arrows, the cooled gas leaves the anode through the openings of the T-tube, circulates across the bulb into the cathode region and there is drawn into the cathodic jet, which completes the cycle. The cathodic jet is produced at the cathode tip due to magnetic constriction of the hot gases. This jet can have a high velocity, in the order of 500 to 1000 feet per second. The diameter of the anode tip hole 35 is preferably made approximately $\frac{1}{4}$ to $\frac{1}{2}$ of the diameter of the arc plasma which would be produced if a conventional anode without hole were utilized.

A feature of the design of the anode electrode according to this invention and as shown in FIGS. 1 and 1A is the cooling of the hot plasma gas before it reaches the bulb. This cooling removes a considerable part of the energy that is otherwise carried from the arc directly to the bulb by convection. In addition, the axial hole 35 in the anode constricts the arc since it provides a more ready path for the arc to travel than the portion of the anode surrounding the hole. This produces a considerable increase of the arc brightness and radiance in the anode region. This is a desirable improvement as the average brightness of compact arc lamps operating on direct current with conventional anodes is relatively low because the anode region is quite diffuse in comparison to the extremely constricted cathode region.

In addition, through the use of a hollow anode, the arc plasma is considerably more concentrated in the anode vicinity and the average brightness of the arc is substantially increased. Also, the arc is perfectly centered with respect to the cathode-anode axis independent of the lamp's position in relation to gravity.

The constriction of the arc can be increased further through the use of a cathode 47 according to FIG. 2. This cathode is designed to operate with the anode of FIGS. 1 and 1A. The tip 48 of this cathode is pointed but is relatively short and small. It is brazed or welded to the end of the cathode tube sealing it with respect to cooling fluid which is supplied from a source (not shown) through an entrance conduit 50. The fluid returns through the space between the inner wall of electrode tube 47 and the outer wall of conduit 50. The tip 48 is cooled by the cooling liquid spraying from the end of the entrance conduit 50. Getter material, formed by several windings of titanium or tantalum wire, is provided on the tip 48.

The cathode tube 47 is formed with a shank portion 52 which is directly cooled by the fluid from conduit 50. The shank 52 has a cylinder 54 thereon which is spaced from the shank and which has several openings 55. In this arrangement the circulating plasma gas can enter openings 55 and flow directly over the liquid cooled cathode shank 52 until it enters the cathodic plasma jet at the cathode tip 48 (as indicated by arrows). By using this cathode design a part of the circulating gas flow is accelerated and precooled directly by the cathode before entering the cathodic jet. This causes an additional constriction of the arc over its entire length and an increase

of brightness and radiance, when compared to arcs operating from a conventional cathode as shown in FIG. 1 under otherwise equal conditions.

The lamps of the subject application can use conventional fills, e.g. 3 to 18 atmospheres of xenon, such as described in my Patent No. 2,974,249. They also can use a halogen additive as described in the aforementioned application. Other additives can be utilized, if desired, to vary the color of the plasma, i.e. use gases which ionize more or less readily.

While preferred embodiments of the invention have been described above, it will be understood that these are illustrative only, and the invention is limited solely by the appended claims:

15. A compact arc discharge lamp comprising an outer envelope, a pair of electrode bodies to which electrical current is to be applied mounted within said envelope with the ends of said electrode bodies being oppositely disposed to produce an arc therebetween, and at least one of said electrode bodies formed with a passage having an entrance and an exit end within the interior confines of the envelope for circulating hot gas therethrough within the interior of the envelope.
20. 2. A lamp as set forth in claim 1 wherein the hot gas circulated is the plasma gas formed by the arc discharge.
25. 3. A compact arc discharge lamp comprising an outer envelope, a pair of electrode bodies to which electrical current is to be applied mounted within said envelope with the ends of said electrode bodies being oppositely disposed to produce an arc discharge therebetween, one of said bodies formed with a passage having an entrance end and an exit end communicating with the interior of said envelope through which the hot gas produced by the arc discharge circulates within the envelope, and means for cooling the gas circulating through said passage.
30. 4. A lamp as set forth in claim 3 wherein said cooling means comprises means for circulating fluid within said body in a heat exchange relationship with the gas circulating through said passage.
35. 5. A lamp as set forth in claim 2 wherein said electrode bodies comprise an anode and cathode, said gas-circulating passage formed in the anode electrode, the entrance end of said passage being in the line of the arc discharge produced between the anode and cathode electrodes.
40. 6. A lamp as set forth in claim 5 wherein the entrance end of said passage for the gas lies opposite the cathode electrode and is constructed to constrict the arc.
45. 7. A lamp as in claim 5 wherein said passage includes at least one exit passage in the anode which conducts the gas flow away from the anode.
50. 8. A lamp as set forth in claim 7 wherein the passage is generally T-shaped.
55. 9. A lamp as set forth in claim 7 wherein the exit passage conducts the circulated gas toward the wall of the envelope.
60. 10. A lamp as set forth in claim 5 further comprising a passage formed in said cathode having an entrance end and an exit end communicating with the interior of the envelope through which the plasma gas also can circulate.
65. 11. A lamp as set forth in claim 3 further comprising a passage in the other of said electrode bodies, said passage having an entrance end and an exit end which are both in communication with the interior of the envelope through which the hot gas produced by the arc discharge also circulates within the envelope.
70. 12. A lamp as set forth in claim 11 further comprising means for cooling the gas circulating through the passage of said other body.
75. 13. A lamp as set forth in claim 10 wherein the cathode passage directs the gas flow from the cathode toward the anode passage.
14. A lamp as set forth in claim 12 wherein said cooling means for the gas circulating in the passage of the other body comprises means for circulating fluid within

said other body in a heat exchange relationship with the gas circulating the said passage of said other body.

15. A lamp as set forth in claim 3 wherein said electrode bodies comprise an anode and cathode, said gas-circulating passage formed in the anode electrode, the entrance end of said passage being in the line of the arc discharge produced between the anode and cathode electrodes.

16. A lamp as set forth in claim 15 wherein the entrance end of said passage for the gas lies opposite the cathode electrode and is constructed to constrict the arc.

17. A lamp as in claim 15 wherein said passage includes at least one exit passage in the anode which conducts the gas flow away from the anode.

18. A lamp as set forth in claim 17 wherein the passage is generally T-shaped.
